UNITED STATES PATENT OFFICE.

WILLIAM R. McKEEN, JR., OF OMAHA, NEBRASKA, ASSIGNOR, BY MESNE ASSIGNMENTS, TO McKEEN MOTOR CAR COMPANY, OF OMAHA, NEBRASKA, A CORPORATION OF NEW JERSEY.

INTERNAL-COMBUSTION ENGINE.

1,101,705.

Specification of Letters Patent. Patented June 30, 1914.

Application filed June 12, 1907. Serial No. 378,574.

To all whom it may concern:

Be it known that I, WILLIAM R. McKEEN, Jr., residing at Omaha, in the county of Douglas and State of Nebraska, have invented certain new and useful Improvements in Internal-Combustion Engines, of which the following is a full, clear, and exact description, such as will enable others skilled in the art to which it appertains to make and use the same.

This invention relates to engines, and with regard to the more specific features thereof to those of the internal combustion type.

One of the objects thereof is to provide an efficient, practical engine susceptible of ready inspection and quick repair.

Another object is to provide an engine of the above type in which the more vulnerable parts may be removed as a unit.

Another object is to provide an engine in which the valves are so formed and disposed as to consume a minimum of space and provide a wide port opening without sacrifice of simplicity and durability of construction.

Another object is to provide a multiple-cylinder engine of the type first mentioned in which the several cylinders with associated parts are rigidly held in fixed relation one to another.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of my invention, Figure 1 is an elevation thereof, certain parts being shown in section in order to illustrate the construction more clearly, the plane of section being taken upon the line $a-a$ of Fig. 2. Fig. 2 is a plan view, certain parts being shown in section in order to more fully disclose the structure, the plane of section being taken on the line $b-b$ of Fig. 1. Fig. 3 is a detail sectional elevation of a cylinder head with valves.

Similar reference characters refer to similar parts throughout the several views of the drawings.

As conducive to a ready understanding of certain features of this invention, it may here be noted that in engines of the internal combustion type, on account of the number of more or less vulnerable points there is often a loss of valuable time in locating the defective part in the event of the engine becoming inoperative. Moreover, when the cause of the breakdown is found, considerable time is often consumed in gaining access to the affected part, and the services of an expert or the use of special tools or machinery are frequently required to make an effective repair. This liability to more or less protracted delays has interfered with the adoption of motors of this type in relations in which reliable running qualities are essential, and its elimination, as well as the achievement of other valuable ends, is gained in constructions of the nature of that hereinafter set forth.

Referring now to the accompanying drawings, there is shown a casting 1 supported as by the stanchions 2, and so constructed as to form a plurality of cylinders 3, 4 and 5, integral one with another. Upon this casting is removably secured, as by the bolts 6, heads 7, of which, as the same are substantially identical in construction, one only will be described in detail. Head 7 comprises the passages 8 and 9 respectively connected with the inlet and exhaust pipes 10 and 11. In these passages are mounted inlet and exhaust valves 12 and 13, the details of the construction of which will hereinafter be given. There is also formed in the head 7 a passage 14 provided with an air valve 15 and a check valve 16 adapted to admit of the running of the engine under a compressed motive fluid, and these several passages are surrounded by a jacketing space 17 through which the cooling water passes. It may here be noted that certain features herein shown and described are shown, described and claimed in my co-pending application, Serial No. 388,285, filed August 13, 1907, and accordingly are not claimed herein. Also mounted upon head 7 are spark plugs 18, with a suitable controlling lever 19.

Referring now to Fig. 3 of the drawings, in which is shown the construction of valves 12 and 13, the former of which will be described in detail, a collar or cage 20 is fitted

within the wall 21 and terminates at its upper end in a threaded collar 23 which takes into the upper wall 24 of the cylinder head. Beneath the lower edge of the collar or cage 20 is mounted a valve seat 22 for the valve member 25, the stem 26 of which passes upwardly through a depending guide 27 formed upon collar 20, and thence through the collar 23, as shown. From this point, 10 the valve stem passes through a support 28 and terminates in a cross-pin 29 above a cap 30, normally held in raised position as by the spiral spring 31 interposed between this member and an abutment formed upon the support 28. By the use of the independent valve seat ring 22 it may be formed of nickel steel and small in size, thus being well adapted to resist wear and substantially proof against warping. Spring 31 thus 15 tends to hold the valve member 25 in closed position, and the same is depressed to open the port as by the bifurcated lever 32 taking about the stem 26 above nuts 33 and 34 threaded thereon. Lever 32, which is connected with the inlet valve as above described, and lever 35, which bears a similar relation to the substantially identical exhaust valve, are pivotally mounted upon the cylinder head 7 and provided at their outer 20 extremities with the pivoted links 36 and 37 respectively. Link 37 passes through a guide 38 secured to the cylinder head, and terminates in an anti-friction roller 39 co-acting with a cam 40 upon the cam shaft 41. Link 36, passing through a similar guide 25 terminates in operative relation to the cam 42 upon shaft 43.

The check valve 16 is operated by a cam 46 through the lever 44 and link 45. The air 30 valve 15 is bolted to the head at the opposite side and controls the passage 14 which is also controlled by the check valve 16. The precise construction of the air valve 15 and check valve 16 are not features of the present 35 invention, and are not herein claimed, but are shown and described and claimed in my copending application, Serial No. 352,726, filed January 17, 1907, to which reference may be had for a full understanding of such 40 details. It is sufficient for the understanding of the present invention to say that the air valve 15 is adapted to admit and release compressed air to the working space of the cylinder on a two-stroke cycle. The valve 45 50 55 60 65 70 75 80 85 90 95 100 105 110 115 120 125 130

mounted solely upon the heads of the cylinders, and when these heads are removed by the withdrawal of the bolts 6, all these mechanisms may be removed intact.

The operation of the above-described embodiment of my invention is substantially as follows: Assuming that one or more cylinders of the engine are found to be defective in action, the corresponding head or heads are merely removed therefrom, and 70 new heads, which may be stored in accessible position, replaced for the parts removed and the engine started without delay. The defective head may then be taken to the 75 shops, or other location, where the cause of breaking down may be investigated at leisure and the remedy conveniently and efficiently applied. The construction of the inlet and exhaust valves, moreover, is such as to permit of a quick wide port opening, and 80 yet to act positively in withstanding the force of the explosions without injury to the 85 more delicate parts.

It will thus be seen that I have provided 90 an engine in which the several objects of my invention are achieved. The entire construction is simple, and the parts in action are readily held in operative relation one to another. By reason of the integral relation 95 of the several cylinders, the same are held in proper alignment with a minimum of bracing, and other advantages attained as set forth somewhat more fully in the former of my co-pending applications above referred to. The feature whereby the head, with all 100 the parts of the engine subject to derangement, is quickly removed is moreover of the highest practical value.

As many changes could be made in the 105 above construction and many apparently widely different embodiments of this invention could be made without departing from the scope thereof, it is intended that all matter contained in the above description or 110 shown in the accompanying drawings shall be interpreted as illustrative and not in a limiting sense. It is also to be understood that the language used in the following claims is intended to cover all of the generic and specific features of the invention herein 115 described and all statements of the scope of the invention which, as a matter of language, might be said to fall therebetween.

Having described my invention, what I 120 claim as new and desire to secure by Letters Patent is:—

1. In an internal combustion engine, in combination, a cylinder, a head removably mounted upon said cylinder, a spark plug mounted upon said head, a check valve 125 mounted upon said head, a lever controlling said valve and fulcrumed upon said head, driving means, a link connected with said lever and co-acting with said driving means and readily detachable therefrom, and guiding 130

means upon said head coacting with said link whereby said head, spark plug, valve, lever and connecting means may be dismounted as a unit.

- 5 2. In an internal combustion engine, the combination of a head provided with suitable ports and passages; gas inlet and exhaust valves therefor; suitable actuating mechanism for said valves supported and
10 guided completely upon said head; a spark plug mounted in the head; a compressed air inlet and exhaust valve mounted on said

head; actuating means therefor mounted on the head; a check valve adapted to prevent flow of air from the cylinder to the air inlet valve; and a lever mechanism supported by the head and adapted to operate the check valve. 15

In testimony whereof I affix my signature, in the presence of two witnesses.

WILLIAM R. McKEEN, Jr.
